(57) **CLAIM**

The ornamental design for a welding transformer, as shown and described.

DESCRIPTION

FIG. 1 is a perspective view of a first embodiment of the welding transformer;

FIG. 2 is a first end view thereof;

FIG. 3 is a second end view thereof;

FIG. 4 is a first side view thereof;

FIG. 5 is a second side view thereof;

FIG. 6 is a top view thereof;

FIG. 7 is a bottom view thereof;

FIG. 8 is a perspective view of a second embodiment of the welding transformer;

FIG. 9 is a first end view thereof;

FIG. 10 is a second end view thereof;

FIG. 11 is a first side view thereof;

FIG. 12 is a second side view thereof;

FIG. 13 is a top view thereof; and,

FIG. 14 is a bottom view thereof.

The broken lines in the drawings depict unclaimed environmental subject matter.

The broken away symbols in the drawings indicate that any portion of the article beyond what is shown forms no part of the claimed design.
